UNITED STATES PATENT OFFICE.

JAMES B. LADD, OF PHILADELPHIA, PENNSYLVANIA, ASSIGNOR TO UNITED STATES CAST IRON PIPE AND FOUNDRY COMPANY, OF BURLINGTON, NEW JERSEY, A CORPORATION OF NEW JERSEY.

PATTERN-RAMMING MACHINE FOR PIPE-MOLDING.

1,272,278.

Specification of Letters Patent.

Patented July 9, 1918.

Application filed March 6, 1917. Serial No. 152,578.

To all whom it may concern:

Be it known that I, JAMES B. LADD, a citizen of the United States of America, and a resident of the city and county of Philadelphia, in the State of Pennsylvania, have invented certain new and useful Improvements in Pattern-Ramming Machines for Pipe-Molding, of which the following is a true and exact description, reference being had to the accompanying drawings, which form a part thereof.

My present invention relates to molding apparatus and comprises improvements especially devised and adapted for use in pipe molding apparatus of the well known type in which the body of a vertical pipe mold is formed by drawing up out of the mold a main ramming pattern comprising a stem portion about which the loose mold forming sand is charged, and a lower body or ramming portion of greater cross sectional area than the stem which forces the sand outwardly and compresses it between the wall of the flask and the ramming portion of the pattern as the latter is drawn up through the mold flask.

The primary object of the invention is to provide simple and effective mechanism whereby the main ramming pattern or patterns, and preferably also the auxiliary riser pattern or patterns for completing the upper ends of the molds may be readily, accurately and expeditiously manipulated in the mold forming operation proper and in operations incidental thereto.

A distinguishing characteristic of my improved means is the use of a block and tackle or analogous gear, advantageously actuated by an electric motor or the like, for simultaneously applying the necessary upward pull to the main ramming patterns and an opposing downward reactive thrust to the flask.

The various features of novelty which characterize my invention are pointed out with particularity in the claims annexed to and forming a part of this specification. For a better understanding of the invention, however, and of the specific objects attained by it, reference should be had to the accompanying drawings and descriptive matter in which I have illustrated and described a preferred embodiment of my invention.

Of the drawings:

Figure 1 is a side elevation partly in section of a portion of a pipe molding plant in which my invention is utilized;

Fig. 2 is a plan view of the apparatus shown in Fig. 1;

Fig. 3 is an end elevation of the upper part, and Fig. 4 an end elevation of the lower part of the portion of the mechanism shown in Figs. 1 and 2 with some parts shown in section;

Fig. 5 is a somewhat diagrammatic plan of the plant shown in part in Figs. 1 and 2;

Fig. 6 is an inverted sectional plan taken on the line 6—6 of Fig. 4;

Fig. 7 is a partial section taken on the line 7—7 of Fig. 4; and

Fig. 8 is a partial sectional elevation taken on the line 8—8 of Fig. 5.

In the drawings I have illustrated the application of my invention to pipe molding apparatus of the type in which a series of vertical pipe mold flasks A, shown as double mold flasks are mounted at the periphery of a turn-table B intermittently rotated to move the flasks successively into and out of a molding station at which the molds are formed by the ramming or compressing action of the various patterns employed. Each flask, as shown, is of the two mold type, and the various patterns are in connected pairs. A main pattern hoist is employed to lower the two main ramming patterns K down into the flask, and after the flask has been charged with sand, to draw these patterns up out of the mold and simultaneously with the latter operation to force a mold engaging element downward against the mold to apply a downward thrust to the flask substantially balancing the upward pull exerted on the flask by the ramming patterns K. The mold engaging element carries riser patterns h which are forced into, and form the upper portion of the mold on the downward movement of said element. Also located at the molding station is socket pattern forming mechanism P vertically adjustable into and out of operative engagement with a flask at the molding station and comprising means for centering the lower ends of the ramming patterns K preparatory to the mold charging operation, and for forcing the socket patterns p into the mold after the latter is

charged to thereby form the lower end, or socket portion of the mold.

The molding apparatus disclosed, in its general features to which reference has just 5 been made forms no part of my invention, but does contain many novel features disclosed and claimed in the application, Serial No. 152,659, of Louis R. Lemoine, filed March 6, 1917. My present invention does 10 consist, however, in various specific features of the mechanism by which the main ramming patterns K and the riser patterns h are supported and manipulated. The socket pattern mechanism partially illustrated here- 15 in also contains specific features of novelty fully disclosed and claimed in my copending application, Serial No. 152,577, filed March 6, 1917.

The mechanism for manipulating the patterns K and h is mounted on a superstructure which in the preferred construction illustrated, is in the form of a built up crane arm C rotatively mounted at one end on the central column B' of the turn-table. At its 20 outer end the crane C is supported on a track D concentric with the column B' and lying at an appreciable distance beyond the path of the flasks A. The crane C is provided with wheel C' running on the track D, 25 and in the construction shown one of the wheels is geared to a motor E mounted on the crane and employed to give the latter such adjustments about the axis of the column B' as may be desired.

30 Mounted on the crane C are track rails C² on which run the supporting wheels F' of a carriage or truck F. The truck F is adjusted radially of the turn-table along the rails C² by means of a hydraulic cylinder G mounted on the crane C and having its piston connected by the stem G' to the carriage F. Mounted on, and forming part of the carriage F, is a vertical cage or tower structure a portion of which extends upward 35 above the track rails C² while another portion extends downward between the track rails. In the drawings F¹⁰ represents vertical elements and F¹¹ horizontal elements of the tower structure.

40 Mounted in the tower structure is a vertically movable mold engaging element H comprising a pair of vertical strut members H' shown as tubular, and upper and lower crosshead members H² and H³ respectively, rigidly connected to the upper and lower ends of the struts. The riser patterns h are detachably secured to the under side of the crosshead H² by means of rotatable clamping devices H⁴. The mold engaging element H is guided in its vertical movements by means 45 of guide clips F¹² secured to the tower structure and engaging ribs H⁴ on the strut members H' as is shown best in Fig. 6. The crosshead H² is also formed with guide ribs 50 H⁵ which work between guides F¹⁴ forming

a part of the tower structure (see Figs. 2 and 3). The element H is connected to the upper end of the tower structure by means of hydraulic cylinders H⁶ secured to the element H, and the pistons I working in these 50 cylinders. As shown, the cylinders H⁶ are for convenience, mounted within the upper ends of the tubular struts H', and the hollow stems I' of the pistons I are pivotally connected by trunnions on the crossheads I² at 55 their upper ends to the beams F¹² carried at the top of the tower. The admission of pressure fluid to, and its exhaust from the upper ends of the cylinder H⁶, is controlled by a two-way valve H¹⁰ mounted on the carriage F and connected to a supply pipe H⁹ and an exhaust pipe H¹², and also connected by piping H¹¹ to the cylinders H⁶ through the hollow piston stems I'. In one of its two co-operative positions the valve H¹⁰ connects the cylinders H⁶ to the supply pipe H⁹, and in the other it connects them to the exhaust pipe H¹². The operating stem H¹³ of the valve H¹⁰ (see Fig. 3) is connected to the arm of a rock-shaft H²⁰ which may be 60 normally rotated through either of two depending levers H¹⁴, one at each side of the crane C, and may also be operated automatically by means hereinafter described. Mounted on the upper crosshead H² is a 65 pulley block H⁷ comprising pulley wheels H⁸, turning about a horizontal axis, there being two of these wheels in the construction illustrated.

Working in guided relation with the mold 70 engaging element H is a main pattern element comprising a crosshead J and the main ramming patterns K which are detachably secured at their upper ends to said crosshead. As shown, the crosshead J is formed 75 with vertical guide ways J' which receive the vertical guide ribs H¹⁵ formed on the adjacent sides of the two struts H'. In the construction shown, the crosshead J is formed with sockets to receive the tapered 80 upper ends K' of the patterns K which are secured in place by nuts K² on the reduced threaded upper ends of the patterns. The patterns K may well be, and are shown as being of the type disclosed and claimed in 85 the patent granted September 2, 1913, to Roswell G. Jaimes, No. 1,072,235. The riser patterns fit snugly about the longitudinal ribs K³ formed on the small diameter portion of the pattern K so that the main patterns K are guided by the riser patterns in 90 the pattern ramming operation.

95 Mounted on the crosshead J is a pulley block J² comprising as shown, two pulley wheels J³. The pulley blocks H⁷ and J² 100 mounted on the flask engaging frame H and on the crosshead J respectively, form part of a block and tackle connection of which a wire cable L, or other suitable flexible power transmitting element is the fall. In the con- 105

struction shown, the standing end of the fall L is connected to the upper end of the tower structure of the carriage F at L', and the fall runs from the point L' down around 5 one of the pulleys J⁸ then up over one of the pulleys H⁹, then down around the second pulley J⁹, then up to and over the second pulley H⁸, and thence the running end of the fall passes to a horizontal winding drum 10 M. The latter is journaled on the carriage F, and is driven through suitable speed reducing gearing by the electric motor N also mounted on the carriage. At M' I have conventionally illustrated a brake mechanism 15 which may be employed as is usual with winding drums of this character, to directly control the movements of the winding drum. In the preferred plant arrangement shown 20 in Fig. 5, there are two molding stations proper at each of which there is located a socket pattern ramming mechanism collectively indicated herein by the reference symbol P and which may well be, and in so far as it is herein shown, is of the type fully 25 disclosed in my said copending application, Serial No. 152,577. The principal purpose of duplicating the molding stations is to avoid loss of time in changing the socket patterns in changing from one style or size 30 of mold to another. With this arrangement the socket pattern mechanism can be changed at one station while the molding operation is going on at the other station. At each station there is located a controller n for the 35 winding drum motor N, and a controller b for the motor B² by which the turn-table B is intermittently rotated. At each molding station are also located controller levers p¹ and p² controlling the adjustment and operation of the corresponding socket pattern 40 mechanism P. With the carriage F in position for operation at either station one or the other of operating levers H¹⁴ for the valve H¹⁰ will be within convenient reach of 45 the operator manipulating the other controllers just referred to located at that station. The various controllers which need to be manipulated in the molding operations performed at either station are thus conveniently disposed within the control of a single attendant at a single convenient place adjacent the molding stations. The controller e for the crane adjusting motor E is located at a convenient spot which need not necessarily be at either molding station. Neither 50 is it necessary for the controller, (not shown) for the carriage adjusting cylinder G to be located at either molding station, since neither the crane C nor the carriage F 55 ordinarily need to be adjusted after being put in the proper position for operating at one molding station until it is desired to interrupt operation at that molding station.

Advantageously stools or supports Q are 60 arranged at one side of the molding stations

to support the main rammer and riser patterns not in use. As shown in Fig. 8, these stools or supports comprise open frames through which the bodies of the ramming patterns are lowered, the patterns being supported by the engagement with the frames of the flask engaging flanges or follower plate h' connected to the riser patterns h. The enlarged heads K⁴ at the upper ends of the main ramming patterns K engage the 70 riser patterns h and prevent the ramming patterns K from passing completely down through the riser patterns.

In the normal operation of the apparatus disclosed, the crane C and the carriage F 80 thereon, with the proper riser and main ramming patterns h and K in place, are adjusted to bring the patterns into the proper position, at one or the other molding station, in which these patterns are in substantial alignment with the corresponding socket patterns p. The turn-table B is then adjusted to bring a flask A into register with the patterns, after which the winding drum M is manipulated to lower the ramming patterns 90 K into place in the flask, and the corresponding socket pattern mechanism is brought into operative relation with the lower end of the flask. The lower ends of the ramming patterns K then pass down into, and are centered by the socket patterns p. The next step in the operation is to charge the flasks with sand which loosely fills the space in the flasks surrounding the ramming patterns. Suitable sand conveyer mechanism not illustrated will ordinarily be employed to facilitate the charging of the flasks. 100

During the initial operations already described, the mold engaging element H is maintained in the elevated position shown 105 in Figs. 1 and 2 by the pressure fluid admitted to the cylinders H⁶, and acting between the upper end walls thereof and the upper sides of the pistons I. I prefer also to maintain pressure in the cylinders H⁶ 110 during the movement of the mold engaging element into engagement with the mold and the initial portion of the main pattern ramming operation. This movement and operation is brought about by starting the 115 motor N into operation to wind up on the drum M, the running end of the fall L which forms a part of the block and tackle connection between the main ramming patterns K and the mold engaging element H. 120 This tends to draw the mold engaging element downward and the main ramming patterns upward. The parts are preferably so proportioned that with the normal pressure at which the pressure fluid is supplied to 125 the cylinders H⁶, the normal resistance to the upward movement of the patterns K through the sand is largely in excess of the resistance to the full downward movement of the mold engaging element. The riser 130

patterns *h* are consequently forced down into the mold the full depth, and the flange plate *h'* brought into engagement with the upper end of the flask, before the main ramming patterns *K* start to move upward. After the mold engaging element is thus seated on the flask and further relative movement between these parts is thus prevented, the main ramming patterns *K* begin to move upward and the upward movement of the main ramming patterns is continued until they are drawn clear of the mold. After the mold engaging element is firmly seated on the flask, and the main patterns are started on their upward movement, the pressure in the cylinders *H⁶* is preferably released to insure that when the patterns *K* approach the upward limit of their movement and the resistance to their movement decreases, there will be no tendency for the mold engaging element *H* to lift. After the patterns *K* are entirely withdrawn from the molds the pressure fluid is again admitted to the cylinders *H⁶*, whereupon the mold engaging element *H* and the riser patterns *h* carried by it are lifted clear of the flask. Prior to, or during the initial portion of the operation of drawing the main patterns *K* out of the molds, the socket patterns *p* in use are forced up by the corresponding socket pattern mechanism *P* to form the lower portion of the mold. After this is accomplished and the lower ends of the main patterns *K* have moved out of engagement with the socket patterns *p* the latter may be retracted and the socket pattern mechanism *P* may be moved out of operative relation with the flask, so that when the main patterns *K* and the riser patterns *h* are lifted above the flask, the table *B* may be advanced to bring a following flask *A* into register with the patterns.

Operated in the manner described, the cylinders *H⁶* and pistons *I* form a yielding support for the pattern drawing mold compacting mechanism above the flasks which normally supports the weight of the mechanism and tends to hold the flask engaging element of the press above the flasks, but which yields to permit the flask engaging element to engage a flask when the main pattern puller is subjected to the reaction of the mold material being compacted therein.

In lieu of controlling the maintenance of the sustaining force thus exerted by the cylinders *H⁶* and pistons *I* by the manual actuation of the levers *H¹⁴*, this may be brought about automatically, as has been hereinbefore indicated. One arrangement for accomplishing this is illustrated in the drawings and comprises a pair of levers *H²³* and *H²⁵*, pivotally connected to the frame-work *F¹⁰*, at lower and upper levels respectively.

These levers have their outer ends connected by links *H²²* and *H²⁴* respectively to the opposite ends of a lever *H²¹*, connected to and extending in opposite directions from the rock-shaft *H²⁰*.

A trip *J²⁵* is pivoted at *J²⁰* to the cross-head *J*, and is prevented from turning downward from its normal horizontal position by engagement with a stop pin *J²⁷*. The trip *J²⁵* is adapted to successively engage the inner ends of the levers *H²³* and *H²⁵* during the upward movement of the block *J*, in drawing the main ramming patterns out of the mold. When the trip *J²⁵* engages the lever *H²³* it shifts the latter, (and also lever *H²⁵*) from the full to the dotted line position of Fig. 3. This adjusts the stem *H¹³* of valve *H¹⁰* to connect the upper ends of cylinders *H⁶* to exhaust and thereby does away with the normal sustaining force exerted by the cylinders *H⁶* and the pistons *I*. As the crosshead *J* continuing its upward movement approaches its uppermost position the trip *J²⁵* engages the lever *H²⁵* and shifts it back into its full line position and thereby adjusts the stem *H¹³* of valve *H¹⁰* to restore pressure in the upper ends of the cylinders *H⁶*. On the subsequent downward movement of the crosshead *J* the trip *J²⁵* moves idly past the levers *H²³* and *H²⁵*.

With the apparatus described it will be apparent that accurate alinement of the main patterns *K* is preserved throughout the pattern ramming operation proper inasmuch as the patterns travel in guides held in rigid engagement with the flask in which the mold is being formed. The upward pull exerted on the flask through the sand by the resistance of the latter to the movement of the patterns *K*, which amounts to many tons in some cases, is substantially balanced by the downward thrust imparted to the flask by the mold engaging element *H* indirectly through the riser patterns *h* and the sand, and directly through the flask engaging flange plate *h'*. By suitably proportioning the parts and in particular, by increasing the number of pulley wheels in the pulley blocks *H'* and *J²* of the block and tackle connection, the opposite thrusts exerted on the flask may be brought into almost mathematical balance but such refinement is in general unnecessary. To secure satisfactory results it is in general only essential to insure that the upward pull on the flask due to the upward movement of the patterns *K* does not exceed the downward thrust which the mold engaging element *H* simultaneously exerts on the flask by an amount as large as the weight of the flask and the sand contained therein.

The apparatus disclosed is obviously adapted to speedy manipulation both in the mold forming operation proper and in the

interchange of pattern necessary in changing from one style or size of pipe mold to another. To effect this change the crane C and carriage F are adjusted to bring the patterns K and h supported thereby over an empty steel frame Q whereupon the patterns are dropped into engagement with the latter and are then disconnected therefrom. The crane C is then adjusted to bring the carriage F over the steel frame Q in which are held the patterns K and h next to be used, and the latter are then connected to the mechanism of the carriage F. The operations of connecting and disconnecting the patterns K and h are simple and may be quickly performed. The operation of changing the socket patterns ordinarily takes more time, but by the use of the two molding stations the proper socket patterns for the next molding operation may be made at one molding station while molding operations are being performed at the other molding station. The formation of the molds does not require any hand work whatever.

With the mechanism disclosed, the necessary headroom above the flask level is reduced to a practical minimum, and the use of the block and tackle connection and the motor driven winding drum M contributes to a maximum speed of operation and minimizes the cost of operation.

While in accordance with the provisions of the statutes I have illustrated and described the best form of my invention now known to me, it will be apparent to those skilled in the art that changes can be made in the form of my invention without departing from its spirit, and that some features of my invention may be used without a corresponding use of other features of the invention.

Having now described my invention, what I claim as new and desire to secure by Letters Patent, is:—

1. A pattern hoist for pulling a ramming pattern up out of a vertical pipe mold comprising in combination a support, vertically movable pattern and mold engaging elements carried by said support, and a block and tackle connection between said elements for simultaneously applying an upwardly acting force to said pattern element and a downwardly acting force to said mold engaging element.

2. A pattern hoist for pulling a ramming pattern up out of a vertical pipe mold comprising in combination a support, vertically movable pattern and mold engaging elements carried by said support, a block and tackle connection between said elements for simultaneously applying an upwardly acting force to said pattern element and a downwardly acting force to said mold en-

gaging element, and means for adjusting 65 said mold engaging element relative to said support.

3. A pattern hoist for pulling a ramming pattern up out of a vertical pipe mold comprising in combination a support, vertically 70 movable pattern and mold engaging elements carried by said support, a block and tackle connection between said elements for simultaneously applying an upwardly acting force to said pattern element and a 75 downwardly acting force to said mold engaging element, and a yielding vertically adjustable connection between said mold engaging element and said support.

4. A pattern hoist for pulling a ramming 80 pattern up out of a vertical pipe mold comprising in combination a support, vertically movable pattern and mold engaging elements in guided relation with said support, a block and tackle connection between 85 said elements for simultaneously applying an upwardly acting force to said pattern element and a downwardly acting force to said mold engaging element, and fluid pressure adjusting means connecting said mold 90 engaging element and said support and comprising co-operating piston and cylinder elements relatively movable in a vertical direction.

5. A pattern hoist for pulling a ramming 95 pattern up out of a vertical pipe mold comprising in combination a support, vertically movable pattern and mold engaging elements in guided relation with said support, and a block and tackle connection between 100 said elements for simultaneously applying an upwardly acting force to said pattern element and a downwardly acting force to said mold engaging element, said connection comprising a fall having its standing 105 end connected to said support.

6. A pattern hoist for pulling a ramming pattern up out of a vertical pipe mold comprising in combination a support, vertically 110 movable pattern and mold engaging elements in guided relation with said support, a block and tackle connection between said 115 elements for simultaneously applying an upwardly acting force to said pattern element and a downwardly acting force to said mold engaging element, said connection comprising a fall having its standing end connected to said support and means mounted on said support for applying a pull to the running end of said fall.

7. A pattern hoist for pulling a ramming pattern up out of a vertical pipe mold comprising in combination a support, vertically 120 movable pattern and mold engaging elements in guided relation with said support, a block and tackle connection between 125 said elements for simultaneously applying an upwardly acting force to said pattern element

and a downwardly acting force to said mold engaging element, said connection comprising a fall having its standing end connected to said support and means for adjusting said 5 mold engaging element relative to said support.

8. A pattern hoist for pulling a ramming pattern up out of a vertical pipe mold comprising in combination a support, vertically 10 movable pattern and mold engaging elements in guided relation with said support, a block and tackle connection between said elements for simultaneously applying an upwardly acting force to said pattern element and a downwardly acting force to said mold engaging element, said connection comprising a fall having its standing end connected to said support and a yielding vertically adjustable connection between 15 said mold engaging element and said support.

9. A pattern hoist for pulling a ramming pattern up out of a vertical pipe mold comprising in combination a support, a vertically 20 movable mold engaging element mounted in said support and comprising vertical members, a pattern secured to the lower ends of said members, a pattern element comprising a vertically movable crosshead 25 in guided relation with said members, a main ramming pattern in guided relation with the first mentioned pattern, and a block and tackle connection between said crosshead and the upper ends of said members 30 for simultaneously applying an upwardly acting force to said pattern element and a downwardly acting force to said mold engaging element.

10. A pattern hoist for pulling a ramming pattern up out of a vertical pipe mold comprising in combination, a support, a vertically 40 movable mold engaging element mounted in said support in guided relation therewith and comprising vertical members, a pattern secured to the lower ends of said 45 members, a pattern engaging element comprising a vertically movable crosshead in guided relation with said members, a main ramming pattern in guided relation with the 50 first mentioned pattern and means for simultaneously applying an upwardly acting force to said pattern element and a downwardly acting force to said mold engaging element.

11. A pattern hoist for pulling a ramming pattern up out of a vertical pipe mold comprising in combination a support, a vertically 55 movable mold engaging element mounted in said support and comprising upper 60 and lower crossheads, and tubular connecting struts, an adjustable connection between said element and support comprising piston chambers located in the upper ends of said tubular struts and pistons working therein 65 and connected to said support, a pattern ele-

ment comprising a crosshead in guided relation with said struts and a ramming pattern secured to said crosshead, and a block and tackle connection between the upper crosshead of said mold engaging element and the 70 crosshead of said pattern element.

12. A pattern hoist for pulling a ramming pattern up out of a vertical pipe mold comprising in combination, a support, a vertically 75 movable mold engaging element mounted in said support and comprising upper and lower crossheads and connecting struts, the latter being in guided relation with said support, a pattern secured to the lower crosshead of said element, a pattern engaging element comprising a vertically movable crosshead in guided relation with said struts and a main ramming pattern in guided relation with the first mentioned pattern, and a block 80 and tackle connection between said elements comprising a pulley block mounted on the upper crosshead of the mold engaging element and a pulley block mounted on the crosshead of the pattern element.

13. A pattern hoist for pulling a ramming pattern up out of a vertical pipe mold comprising in combination, a support, a vertically 85 movable mold engaging element mounted in said support and comprising upper and lower crossheads and connecting struts, the latter being in guided relation with said support, a riser pattern secured to the lower crosshead of said element, a pattern engaging element comprising a vertically movable crosshead in guided relation with said struts, and a main ramming pattern passing through and guided by said riser pattern, and a block and tackle connection between 90 said elements comprising a pulley block mounted on the upper crosshead of the mold engaging element, a pulley block mounted on the crosshead of the pattern element and a fall the standing end of which is connected to said support.

14. In pipe molding apparatus the combination with a vertical flask and its supporting means, of a support extending over the flask, a carriage mounted on and horizontally movable with respect to said support, vertically movable mold engaging and pattern elements in guided relation with one another and said carriage, a rotatable motor mounted on said carriage and power transmitting connections between said motor and said elements for simultaneously applying oppositely acting forces to said elements.

15. In pipe molding apparatus the combination with a vertical flask and its supporting means, of a support extending over the flask, a carriage mounted on and horizontally adjustable with respect to said support, vertically movable mold engaging and pattern elements in guided relation with said carriage, a motor mounted on said carriage, and a block and tackle connection between 115 120 125 130

said elements comprising a fall the running end of which is operatively connected to said motor.

16. In pipe molding apparatus the combination with a vertical flask and its supporting means, of a support extending over the flask, a carriage mounted on and horizontally adjustable with respect to said support, vertically movable mold engaging and pattern elements in guided relation with said carriage, a motor mounted on said carriage, and a block and tackle connection between said elements comprising a fall the running end of which is operatively connected to said motor and the standing end of which is connected to said carriage.

17. In pipe molding apparatus the combination with a vertical flask and its supporting means, of a support extending over the flask, a carriage mounted on and horizontally adjustable with respect to said support, vertically movable mold engaging and pattern elements in guided relation with said carriage, a motor mounted on said carriage, a block and tackle connection between said elements comprising a fall the running end of which is operatively connected to said motor and means for adjusting said mold engaging element relative to said carriage.

18. In a pipe molding plant the combination with a turn table and a series of vertical flasks carried thereby, of an idle pattern support located adjacent said turn table, a crane arm mounted above the flasks to turn about the turn table axis and a pattern hoist mounted on said crane arm with freedom for adjustment from one position in which it extends over the path of the flasks into another position in which it extends over said pattern support, and a pair of optionally usable socket pattern mechanisms into co-operative relation with each of which said hoist may be brought.

19. In pipe molding apparatus the combination with a turn-table and a series of vertical flasks carried thereby, of an idle pattern support located adjacent said turn-table, a crane arm mounted above the flasks to turn about the turn-table axis, and a pattern hoist mounted on said crane arm with freedom for adjustment from one position

in which it extends over the path of the flasks into another position in which it extends over said pattern support.

20. In pipe molding apparatus the combination with a turn-table and a series of vertical flasks carried thereby, of a crane arm mounted above the flasks to turn about the turn-table axis and a pattern hoist mounted on said crane arm with freedom for adjustment from one position in which it extends over the path of the flasks into another position in which it lies beyond the path of the flasks.

21. Molding apparatus comprising in combination a support, a mold forming device comprising two co-operative vertically movable elements, means for impressing an upwardly acting force on one of said elements and a reactive downwardly acting force on the other of said elements, and a yielding supporting connection between the last mentioned element and said support.

22. Molding apparatus comprising in combination a support, a mold forming device comprising two co-operative vertically movable elements, means for impressing an upwardly acting force on one of said elements and a reactive downwardly acting force on the other of said elements and a connection between the last mentioned element and said support, normally exerting a yielding supporting force on said element and means for varying said force, and a piston and cylinder supporting connection between said support and said last mentioned element and means for maintaining and for varying an elastic fluid pressure therein.

23. Molding apparatus comprising in combination a support, a mold forming device comprising two co-operative vertically movable elements, means for impressing an upwardly acting force on one of said elements and a reactive downwardly acting force on the other of said elements, a piston and cylinder supporting connection between said support and said last mentioned element and means for maintaining and for varying an elastic fluid pressure therein.

JAMES B. LADD.
